PRODUCTION OF CYCLO-OLEFINIC HYDROCARBONS AND AROMATIC HYDROCARBONS

Herman Pines and Vladimir N. Ipatieff, Chicago, Ill., assignors to Universal Oil Products Company, Chicago, Ill., a corporation of Delaware

No Drawing. Application December 15, 1944,
Serial No. 568,392

6 Claims. (Cl. 260—666)

1

This invention relates to a process for producing cyclic hydrocarbons. More specifically, the invention relates to a process for producing cycloolefins by condensing a diolefinic hydrocarbon having at least 4 carbon atoms per molecule with a monohydric alcohol.

An object of this invention is the condensation of a monohydric alcohol with a conjugated diolefinic hydrocarbon containing at least 4 carbon atoms per molecule.

Another object of this invention is the production of a cyclohexene hydrocarbon by condensing an alkanol with a conjugated diolefin.

A further object of this invention is the production of a cyclohexene hydrocarbon by the condensation of a conjugated diolefin with an alcohol selected from the group consisting of primary and secondary alkanols.

A still further object of this invention is the production of 1,3,5-trimethylcyclohexene by condensing 2-methyl-1,3-pentadiene and isopropyl alcohol.

One specific embodiment of this invention relates to a process for producing a cyclo-olefin which comprises condensing an alkanol and a diolefinic hydrocarbon having at least 4 carbon atoms per molecule in the presence of an acid-acting catalyst at a temperature of from about 150° to about 400° C.

A further embodiment of this invention relates to a process for producing a benzene hydrocarbon which comprises condensing an alkanol and a conjugated diolefin to produce a cyclohexene hydrocarbon, hydrogenating said cyclohexene hydrocarbon to a cyclohexane hydrocarbon, dehydrogenating said cyclohexane hydrocarbon to a benzene hydrocarbon and hydrogen, and utilizing at least a portion of said hydrogen in the hydrogenation of said cyclohexene hydrocarbon.

Cyclohexene and different alkyl cyclohexene hydrocarbons which are obtainable by the process of our invention may be hydrogenated to cyclohexane hydrocarbons or they may be dehydrogenated to benzene and alkyl benzene hydrocarbons.

By the term "condensation" used in this specification and in the claims, we mean the chemical combination of a diolefinic hydrocarbon having at least 4 carbon atoms per molecule and a monohydric alcohol accompanied by the splitting out of water. Thus, 2-methyl-1,3-pentadiene and isopropyl alcohol react at an elevated temperature and preferably in the presence of an acid-acting catalyst to produce 1,3,5-trimethylcyclohexene and water as the principal products of the process.

2

Diolefinic hydrocarbons utilizable in our process contain at least 4 carbon atoms per molecule and are preferably conjugated diolefins in that each of said hydrocarbons contains a system of alternate single and double bonds including two double bonds. Although the reaction of our process proceeds preferably with conjugated diolefins, other diolefins are sometimes usable, particularly when rearrangement occurs at the conditions of the reaction.

Monohydric alcohols utilizable also as starting materials in the process of our invention are generally those of the aliphatic series and preferably are saturated aliphatic carbinols which are also known as alkanols. Alkanols which do not contain a quaternary carbon atom are particularly desirable for condensation with a diolefinic hydrocarbon as herein set forth as alkanols which contain a quaternary carbon atom sometimes yield a substantial proportion of a tertiary olefin rather than the condensation product desired.

Although our process is sometimes carried out in the absence of an added catalyst at suitable operating conditions of temperature and pressure, we prefer to utilize certain catalytic materials to assist in the condensation of a diolefinic hydrocarbon and a monohydric alcohol. Catalysts so utilizable are acid-acting materials and comprise activated alumina, hydrated silica, acid-treated clays; synthetically prepared composites including silica-alumina, silica-alumina-zirconia, alumina-zirconia, silica-alumina-thoria, etc.; acids such as hydrochloric acid, hydrobromic acid, a phosphoric acid, sulfuric acid, or a heteropoly acid as phosphotungstic or phosphomolybdic acid; and also aqueous solutions of hydrolyzable salts such as ferric chloride, magnesium chloride, zinc chloride, ammonium chloride, magnesium acid phosphate, sodium acid sulfate, etc. These materials which we employ as catalysts in our process are acid-acting in the sense that an aqueous solution or suspension thereof in water has a pH below 7.

Our process may be carried out using either batch or continuous types of operation, although the latter is preferable. The process is carried out at a temperature of from about 150° to about 400° C., but preferably at a temperature of from about 175° to about 300° C. The process may be conducted at atmospheric pressure but is preferably effected at a superatmospheric pressure which is generally not in excess of about 100 atmospheres.

The following example is given to illustrate the character of results obtainable by the process

of our invention, although the example is not introduced with the intention of restricting unduly the broad scope of the invention.

1.6 molecular proportions of isopropyl alcohol and 1 molecular proportion of 2-methyl-1,3-pentadiene are commingled and charged to an autoclave containing a 5% by weight solution of ammonium chloride in water. The volume of the ammonium chloride solution is about that of the mixture of a diolefinic hydrocarbon and isopropyl alcohol introduced thereto. After the autoclave and contents are heated at about 250° C. for 3 hours, the heating is discontinued and the reaction mixture is permitted to cool. After cooling, the reaction mixture contains an hydrocarbon layer comprising 1,3,5-trimethylcyclohexene in an amount corresponding to about 35% of the theoretical yield based upon the diolefin charged.

The novelty and utility of the process of the present invention are evident from the preceding specification and example, although neither section is introduced to limit unduly the broad scope of our invention.

We claim as our invention:

1. A process for producing a cyclo-olefinic hydrocarbon which comprises reacting a diolefinic hydrocarbon having at least 4 carbon atoms per molecule and a monohydric alcohol at a sufficient temperature and pressure that condensation of said diolefinic hydrocarbon and monohydric alcohol is the principal reaction of the process.

2. A process for producing a cyclo-olefinic hy-

drocarbon which comprises condensing a diolefinic hydrocarbon having at least 4 carbon atoms per molecule with an alkanol at a temperature of from about 150° to about 400° C.

3. A process for producing a cyclo-olefinic hydrocarbon which comprises condensing a diolefinic hydrocarbon having at least 4 carbon atoms per molecule with an alkanol at a temperature of from about 150° to about 400° C. and at a pressure of from about 1 to about 100 atmospheres.

4. A process for producing a cyclo-olefinic hydrocarbon which comprises condensing a diolefinic hydrocarbon having at least 4 carbon atoms per molecule with an alkanol in the presence of an acid-acting catalyst at a temperature of from about 150° to about 400° C.

5. A process for producing a cyclo-olefinic hydrocarbon which comprises condensing a diolefinic hydrocarbon having at least 4 carbon atoms per molecule with an alkanol in the presence of an acid-acting catalyst at a temperature of from about 150° to about 400° C. and at a pressure of from about 1 to about 100 atmospheres.

6. A process for producing a cyclo-olefinic hydrocarbon which comprises condensing a conjugated diolefinic hydrocarbon with an alkanol in the presence of an aqueous solution of a hydrolyzable metal salt at a temperature of from about 150° to about 400° C. and at a pressure of from about 1 to about 100 atmospheres.
